UNITED STATES PATENT OFFICE.

HENRY F. CONGABLE, OF OAKLAND, CALIFORNIA.

ORCHARD HEATER.

Application filed September 20, 1923. Serial No. 663,778.

To all whom it may concern:

Be it known that HENRY F. CONGABLE, a citizen of the United States, residing at Oakland, in the county of Alameda and State of California, has invented certain new and useful Improvements in Orchard Heaters, of which the following is a specification.

My invention is an improved orchard heater.

10 The object of my invention is to provide a heater, in which the area over which combustion is taking place, is confined to a small space below the combustion chamber, thus effecting a great saving in fuel.

15 A further object is to provide a fresh air inlet means through the combustion chamber.

Further objects and advantages will be more specifically pointed out in the following detailed description.

20 In the annexed drawing in which my invention is illustrated I have shown the preferred embodiment, but it may also be embodied in other forms, and in this application I desire to cover my invention in whatever form it may be embodied.

Figure 1 is a transverse sectional view of my heater.

Figure 2 is a sectional view taken on the line 2—2 of Figure 1.

Figure 3 is a plan view of the air adjusting yoke.

Referring more particularly to the drawing, my heater comprises a tank 1, which has a cover 2, suitably secured thereto. A tube 3 is secured to the cover 2 and extends downwardly to adjacent the bottom of the tank 1. A conduit 4 extends downwardly a short distance into the tube 3, and a combustion chamber 5 is formed on the top of the conduit. The usual holes 6 are formed in the chamber 5 to admit air to support combustion. A light metal chimney 7 fits over the chamber 5 and provides the necessary draft. The conduit 4 is smaller in diameter than the tube 3 and has lugs 8 formed upon it which engage the tube, thus centering the conduit in said tube. An annular air passage 9 is thus formed between the conduit 4 and tube 3.

A tapered adjusting yoke 10 rests on the cover 2 and engages the lower edge of the chamber 5, by moving the yoke 10 inwardly, the chamber is raised above the cover 2, thus admitting the air into the passage 9, the amount of air being determined by the

height of the chamber above the cover. A handle 11 is secured to the yoke 10 and extends through a guide 12, thus enabling the yoke to be easily adjusted as desired.

60 The oil is ignited in the tube 3, and sufficient air is admitted through the passage 9 to support partial combustion, the vapors rise through the conduit 4 into the chamber 5 where complete combustion occurs. Combustion in the tank 1 is confined to the limited area within the tube 3 thus effecting a great saving in fuel.

65 It is easily seen that my invention may be applied to standard smudge pots now in use. The pot becomes the tank 1 and the cover, tube, combustion chamber, etc. are simply placed over it, and an effective heater is thus obtained.

70 Having described my invention, I claim:

75 1. A heater comprising a tank, a cover on said tank, a tube secured to said cover and extending into said tank, a conduit extending into said tube, a combustion chamber positioned at the upper end of said conduit, said conduit being of smaller diameter than the tube to form an air passage, and means to adjust the combustion chamber above the cover to admit air into said air passage.

80 2. A heater comprising a tank, a cover on said tank, a tube secured to said cover and extending into said tank, a conduit extending into said tube, a combustion chamber positioned at the upper end of said conduit, said conduit being of smaller diameter than the tube to form an air passage, and a tapered yoke positioned between the cover and the bottom of the combustion chamber to adjust said chamber above said cover and admit air into said passage.

85 3. A heater comprising a tank, a cover on said tank, a tube secured to said cover and extending into said tank, a conduit extending into said tube, a combustion chamber positioned at the upper end of said conduit, said conduit being of smaller diameter than the tube to form an air passage, lugs formed on said conduit adapted to engage the tube thereby centering the conduit within the tube, and means to adjust the combustion chamber above the cover to admit air into said air passage.

90 4. A heater comprising a tank, a cover on said tank, a tube secured to said cover and extending into said tank, a conduit extending into said tube, a combustion chamber

- positioned at the upper end of said conduit, said conduit having an air passage formed adjacent thereto, and means to regulate said passage to admit the required amount of air 5 to support partial combustion in said tube.
5. A heater comprising a tank, a cover on said tank, a tube secured to said cover and extending into said tank and terminating a short distance from the bottom there- 10 of, a conduit extending into said tube, said conduit being of smaller diameter than the tube, to form an air passage between the conduit and tube and means to regulate the amount of air passing thru said air passage 15 into said tube.
6. A heater comprising a tank, a cover on said tank, a tube secured to said cover and extending into said tank, a conduit extending into said tube and being of smaller di- 20 ameter than the tube, whereby an air pas-

sage is formed between the conduit and tube and means to regulate the amount of air passing thru said air passage into said tube, said means including a tapered yoke.

7. A heater comprising a tank, a cover 25 on said tank, a tube secured to said cover and extending into said tank, a conduit extending into said tube, a combustion chamber positioned at the upper end of said conduit, said conduit being of smaller diameter than the tube to form an air passage, a tapered yoke positioned between the cover and the bottom of the combustion chamber to adjust said chamber above said cover and admit air into said passage, a handle for 30 said yoke whereby the same may be operated and a guide for said handle.

In testimony whereof I affix my signature.

HENRY F. CONGABLE.
